UNITED STATES PATENT OFFICE.

BENJAMIN F. BERRY, OF ST. LOUIS, MISSOURI, ASSIGNOR TO BERRY MACHINE COMPANY, OF ST. LOUIS, MISSOURI, A CORPORATION OF MISSOURI

FEED TABLE FOR PRESSES AND THE LIKE.

Application filed August 23, 1920. Serial No. 405,392.

To all whom it may concern:

Be it known that I, BENJAMIN F. BERRY, a citizen of the United States of America, a resident of the city of St. Louis, in the State of Missouri, have invented certain new and useful Improvements in Feed Tables for Presses and the like, of which the following is a full, clear, and exact description, reference being had to the accompanying drawings, forming a part of this specification.

My invention relates to improvements in feed tables for presses and the like, and is especially useful as applied to printing presses capable of handling sheets of large size. At present it is difficult to handle large sheets of this character for they are not only heavy to lift onto the work table in bundles, but it is also difficult to pick off the top sheet of the stack and feed it into the press from the table. My invention contemplates the use of a vertically movable platform which may be lowered onto the floor where it may be loaded with the paper stock to be printed and then hoisted automatically into its proper position for handling.

Another object of my invention is to automatically separate or comb the top sheets of the stack from the stack proper, so that the operator may have single sheets at hand which may be easily inserted into the press. It is extremely difficult to separate the top sheet from the remainder of the stack when this is done by hand, especially when the sheets are large and are of thin paper stock.

My invention provides for combers or sheet separators acting in conjunction with the automatically moving, stack-lifting mechanism, which combers shall project the top sheets forwardly of the stack toward the work table where the operator may easily feed single sheets into the press, the stack lifting-mechanism being so designed that it will constantly lift the stack while the device is in normal operation, so that the successive top sheets will cooperate with the combers.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention com-

prehends changes, variations and modifications which come within the scope of the claims hereunto appended.

In the drawings, in which like reference numerals indicate like parts throughout the views,

Fig. I is a vertical side elevation of the mechanism.

Fig. II is a plan view thereof.

Fig. III is a vertical section.

Fig. IV is a vertical elevation of the adjustable combers or friction rollers and their mountings.

Fig. V is a detail of the driving connection for the belt conveyor.

A designates a stationary work table having an upright support 1 and an inclined table portion 2. A pair of railings 3 lie along opposite sides of said inclined portion of the table 2 and have mounted upon them a supporting frame 4 comprising a pair of uprights 5, one secured to each of the railings 3 and connected together at their upper ends by a transverse tie rod 6.

Supported by the frame 4 is a vertically movable supply platform 7, said platform being pivotally secured at one end 8 to vertical guides 9 so that it is free to move vertically, said guides being positioned at the lower end of the inclined platform 7. The platform 7 is adapted to receive a stack of sheets B, which are to be raised vertically and fed into the press (not shown).

A series of T-irons 10 are secured to the table 2, parallel to the guide rods 9 so that they form a plane guide for the stack of sheets. The upper ends 11 of the T-irons 10 are bent back toward the table 2 so as to guide the sheets onto the table as they pass these bent ends 11.

The supply platform 7 is lifted by actuating mechanism mounted on the frame 4, said mechanism comprising a motor 12, driving through reduction gearing, a pair of worms, 13 and 14, one at each end of the drive shaft 15. Gear wheels 16 and 17 are mounted on the frame 4 so as to mesh with the worms 13 and 14, respectively. Each of the gear wheels 16 and 17 drives a pair of winding drums 18 and 19, respectively, through shafts 20 and 21, respectively, secured to the gear wheels 16 and 17, respectively. Pairs of flexible hoisting cables 22 and 23, respectively, are attached to the winding drums 18 and 19, respectively, and secured to the

movable platform 7, whereby the platform may be hoisted when the drums are actuated by the motor.

A pair of transverse supporting legs 24 are secured to the under side of the platform 7, these legs being adapted to rest upon the floor when the platform is in its lowermost position and being loaded. In order that the sheets may be easily slid off the stack it is necessary that the stack of sheets be tilted, thus tending to overcome the coefficient of friction between the sheets, the degree of tilt varying with the material used; that is, highly calendered sheets will require a lesser angle of tilt than rough cardboard or matted sheets. The adjustment of the tilting angle is obtained by disconnecting a pair of winding drums from the driving mechanism and then actuating the other pair of drums to lift the platform. This will tilt the platform about its pivot 8.

The means for effecting the tilting of the platform comprises a clutch 25 mounted on the frame 4 and interposed on the shaft 15 between the worms 13 and 14, the shaft 15 being divided into two sections for that purpose. The clutch 25 is operated by means of a handle 26 positioned so as to be convenient to the operator. When the clutch 30 is thrown out, it disengages the worm 14 from the driving connection with the motor 12, and the entire drive is therefore transmitted through the worm 13 and drums 18, the drums 19 remaining idle. Thus it is seen that when the motor is operating and the clutch 25 is thrown so that the worm 14 is inoperative, the platform will tilt about its pivot 8.

In order that the sheets may be delivered singly onto the work table 2, there are provided combing or sheet-separating means, also mounted upon the frame 4, said separating or combing means being mounted below the transverse tie rod 6 and adapted 45 to slide along the vertical guideways 27 secured to the upright members 5 of the frame 4. A transverse bar 28 is supported by the frame 4 and this bar supports the combing apparatus, said apparatus comprising a pair 50 of deflectors 29 engageable with the top corner of the stack of sheets so as to project the sheets forwardly in the direction of the work table, and a pair of serrated friction rollers 30, said rollers being driven by means 55 of a motor 31 mounted upon the transverse bar 28.

The entire combing apparatus comprising the friction rollers, deflectors and motor 31 can be adjusted vertically or horizontally, 60 the vertical adjustment being effected by providing threaded guide extensions 32 at the ends of the bar 28, said guide extensions being adapted to slide in the guideways 27 and being threadedly mounted upon rods 33 65 secured to the tie rod 6. The upper ends

of the threaded rods 33 have beveled gears 34, adapted to mesh with beveled gears 35, the beveled gears 35 being rotatable by means of an adjusting handle 36. The horizontal adjustment is effected by providing 70 slots 37 in the ends of the transverse bar 28 and attaching the guide extensions 32 to the bar 28 by means of bolts 38 extending through said extensions 32 and the slots 37 of the bar 28. 75

When the mechanism is in operation the motor 12 will actuate the hoisting means to lift the supply platform with the stack of sheets, so that the top portion of the stack is projected forwardly toward the work 80 table by means of the deflectors 29, meanwhile permitting the friction rollers 30 to contact with successive top sheets of the stack. The platform 7 and the stack of sheets is being continually lifted during the 85 operation of the device, so that there will always be presented new top sheets to the friction rollers 30, and as these friction rollers 30 are positively driven they will tend to move the top sheets forwardly onto 90 the table 2.

Cooperating with the combing means and mounted on the stationary table 2 are a series of traveling conveyors 39, said conveyors being driven by means of the motor 95 12 through a worm 40 which drives a gear wheel 41, said gear wheel having secured thereto, a sprocket 42. A sprocket chain 43 is driven by the sprocket 42 and drives at its other end a sprocket 44, which in turn 100 drives a shaft 45 to which the series of conveyors are connected.

As it is not necessary nor desirable that the sheets upon the conveyor be disturbed when the supply platform is lowered, there 105 is provided in the driving connection to the conveyors means which will cause the traveling conveyors to travel only in one direction and allow them to remain stationary when the sprocket is rotated in the opposite direction. This driving connection consists of a pawl and ratchet shown in Fig. V. When the sprocket is driven in one direction, the pawl 46 will engage the ratchet 47 to drive the shaft 45, but when the sprocket 110 115 is rotated in the opposite direction, the pawl 46 will move idly on the ratchet 47 and thus will not transmit any motion to the conveyor shaft 45.

Thus it is seen that as a stack of sheets 120 is lifted they will be deflected forwardly by the deflectors 29, the combers 30 cooperating with deflectors to further project the sheets forwardly over the bent ends 11 of the T-bars 10 onto the conveyor 39, and the 125 conveyor belts will carry the sheets down to the end of the work table where the operator may then feed them singly into the press.

The conveyors are so geared that they 130

travel at a higher surface speed than the combers so that they will tend to pull the sheets away from the platform and thus separate or single them out from the stack.

5 Owing to the inclination of the platform 7, the sheets tend to slide downwardly, and even though the sheets are very large and comparatively thin, or rough, they can be very easily forced downwardly from the top 10 of the inclined stack. The inclination of the platform 7 can be varied to obtain the most satisfactory results in the delivery of different kinds of sheets, and in some cases the sheets will slide downwardly by gravity 15 at the top of the inclined stack, so as to be fanned out and carried away by the conveyors 39, without the aid of combers, or the like, above the stack.

I claim:

20 1. In a mechanism of the character described, a tiltably mounted vertically movable supply platform adapted to receive a stack of sheets thereon, and means for delivering said sheets one at a time from said platform.

25 2. In a mechanism of the character described; a vertically movable supply platform adapted to receive a stack of sheets thereon, means for vertically actuating said supply platform, means for delivering said sheets, one at a time, from said platform, and lifting members secured to said supply platform whereby it may be tilted at an angle to the horizontal plane.

35 3. In a mechanism of the character described, a tiltably mounted, vertically movable supply platform adapted to receive a stack of sheets thereon, means for delivering said sheets one at a time from said platform, lifting means for said supply platform and means whereby said platform may be tilted so as to change the inclination of its sheet engaging surface.

40 4. In a mechanism of the character described, a tiltably mounted, vertically movable supply platform adapted to receive a stack of sheets thereon, means for delivering said sheets one at a time from said platform, lifting means at opposite ends of said supply platform, and means for disengaging one of said lifting members so as to tilt said supply platform.

45 5. In a mechanism of the character described, a tiltably mounted, vertically movable supply platform adapted to receive a stack of sheets thereon, means for delivering said sheets one at a time from said platform, lifting means at opposite ends of said supply platform and a clutch for disengaging one of said lifting means so as to tilt said supply platform.

55 6. In a mechanism of the character described, a tiltably mounted, vertically movable supply platform adapted to receive a

stack of sheets thereon, means for delivering 65 said sheets one at a time from said platform, lifting members at opposite ends of said supply platform to actuate said supply platform, a driving gear actuating each of said lifting members, and means for disengaging 70 one of said gears so as to tilt said supply platform.

7. In a mechanism of the character described, a stationary work table, a tiltably mounted, vertically movable supply platform adapted to receive a stack of sheets thereon, means for delivering said sheets one at a time onto said table, lifting members at opposite ends of said table to actuate said supply platform, a driving gear actuating 75 each of said lifting members, and a clutch for disengaging one of said gears so as to tilt said supply platform and change its vertical angle.

8. In a mechanism of the character described, a vertically movable supply platform adapted to receive a stack of sheets thereon, means for delivering said sheets one at a time from said platform, and means for tilting said supply platform, said tilting means comprising winding drums, flexible lifting members wound on said drums and attached to said supply platform and a source of power for actuating said drums.

9. In a mechanism of the character described, a vertically movable supply platform adapted to receive a stack of sheets thereon, means for delivering said sheets one at a time from said platform, said means comprising friction rollers adapted to contact with the successive top sheets of said stack of sheets, said friction rollers being horizontally and vertically adjustable relative to said platform, means for vertically lifting said supply platform constantly during the operation of the device, and means for driving said friction rollers independently of said lifting means.

10. In a mechanism of the character described, a stationary work table, a vertically 110 movable supply platform adapted to receive a stack of sheets thereon, and means for delivering said sheets one at a time over said stationary table, said means comprising a deflector for forwardly projecting the top sheets of said stack of sheets and a traveling conveyor engagable with the forwardly projecting edges of the top sheets and movable over said work table.

11. In a mechanism of the character described, a vertically movable supply platform adapted to receive a stack of sheets thereon, means for vertically lifting said supply platform, and means for delivering said sheets one at a time from said platform, 120 said delivering means comprising a deflector for forwardly projecting the top sheets of said stack, and a traveling conveyor engage-

able with the forwardly projected sheets, said traveling conveyor being actuated by said lifting means.

12. In a mechanism of the character described, a vertically movable supply platform adapted to receive a stack of sheets thereon, and means for delivering said sheets one at a time from said platform, said means comprising a deflector for forwardly projecting the top sheets of said stack, a traveling conveyor engageable with the forwardly projected sheets to carry them away from the stack, and a driving connection for said conveyor adapted to drive the same in only one direction and free to move idly in the other direction.

13. In a mechanism of the character described, a vertically movable supply platform adapted to receive a stack of sheets thereon, and means for delivering said sheets one at a time from said platform, said means comprising a deflector for forwardly projecting the top corner of said stack of sheets, rotatably driven friction rollers adapted to contact with the successive top sheets of said stack of sheets to move them forward and a traveling conveyor engageable with the forwardly projected sheets of said stack to carry them away from the stack, said rollers and supply platform being vertically movable relative to each other during the operation of the device.

14. In a mechanism of the character described, a vertically movable supply platform having an inclined sheet-supporting surface adapted to receive a stack of sheets and adapted to hold the stack in an inclined position, and a support at one side of said platform adapted to receive the sheets passing downwardly from the top of the inclined stack.

15. In a mechanism of the character described, a vertically movable supply platform having an inclined sheet-supporting surface adapted to receive a stack of sheets and adapted to hold the stack in an inclined position, an upright guide at one side of

said platform adapted to engage the lower edges of the inclined sheets, and a support arranged to receive the inclined sheets passing over the upper edge of said upright guide.

16. In a mechanism of the character described, a vertically movable supply platform having an inclined sheet-supporting surface adapted to receive a stack of sheets and adapted to hold the stack in an inclined position, and a sheet feeder arranged at one side of said platform to receive the sheets passing downwardly from the top of the inclined stack.

17. In a mechanism of the character described, a vertically movable supply platform having an inclined sheet-supporting surface adapted to receive a stack of sheets and adapted to hold the stack in an inclined position, and a traveling conveyor arranged to receive the sheets passing downwardly from the top of the inclined stack.

18. In a mechanism of the character described, a vertically movable supply platform having an inclined sheet-supporting surface adapted to receive a stack of sheets and adapted to hold the stack in an inclined position, and a support at one side of said platform adapted to receive the sheets passing downwardly from the top of the inclined stack, said platform being tiltable to vary the angle of said inclined sheet-supporting surface.

19. In a mechanism of the character described, a vertically movable supply platform having an inclined sheet-supporting surface adapted to receive a stack of sheets and adapted to hold the stack in an inclined position, and a traveling conveyor arranged to receive the sheets passing downwardly from the top of the inclined stack, said platform being tiltable to vary the angle of said inclined sheet-supporting surface.

In testimony that I claim the foregoing I hereunto affix my signature.

BENJAMIN F. BERRY.
